HIGH-SPEED DOUBLE-ACTION PRESS

Vasil Georgeff, La Grange Park, Ill., assignor to
 Danly Machine Specialties, Inc., Chicago, Ill.,
 a corporation of Illinois

Application December 21, 1950, Serial No. 202,083

2 Claims. (Cl. 113—38)

1

My invention relates to high speed double action presses and more particularly to an improved double action press capable of operating at greatly increased speed.

Double action presses of the prior art comprise a blank holder adapted to be reciprocated with respect to the bed of the press in order to clamp the work upon the bed in a position to permit dies carried by the inner slide and the bed to do their work. The arrangement is such that the blank holder dwells during the period in which the inner slide performs its operation. Double action presses require comparatively large strokes. For example, in a sixteen-inch draw a double action press of the prior art requires a stroke in the vicinity of thirty-seven inches for the inner slide. The time required for moving the press parts through this long stroke circumscribes the number of operations which can be performed by the press in a given period of time. This is due to the fact that the rate of draw is limited by the characteristics of the metal being drawn. Every metal, as for example, steel, has a limit beyond which it cannot be drawn cold. If it be attempted to draw at a greater linear velocity than the critical velocity, the metal will tear. Accordingly, greater output cannot be obtained by speeding the rotation of the press since this will result in the production of a linear drawing velocity beyond the critical velocity. It will be apparent, therefore, that in event it is desired to produce a large number of pieces within a given period of time, as is the case with presses forming part of a production line, it becomes necessary to employ an increased number of presses. Double action presses are large, heavy and expensive pieces of machinery and require not only capital investment but factory space, as well as maintenance expense in their upkeep.

I have been enabled to construct a double action press having a linkage in which the press cycle is apportioned to the drawing operation and will consume a longer time than the return motion of the inner slide. In this manner the linear velocity of the inner slide during the cycle is greatly reduced. This enables me to speed up the press to a point within which the linear velocity of the draw is within the critical velocity and thus increase the output of the press. For example, my linkage is such that 225° of the 360° cycle is devoted to the downstroke while only 135° of rotation of the driving crank is devoted to the upstroke. By thus lengthening the time of the downstroke I have been enabled to speed a double

2

action press capable of seven strokes per minute to fourteen strokes per minute due to employing a construction having a slow drawing speed with respect to the return speed.

- 5 Some double action presses of the prior art employ two prime movers, one for the blank holder and one for the inner slide. This is due to the fact that the blank holder must dwell during the period the inner slide does its work.
- 10 In my double action press a single prime mover is used to drive both the blank holder and the inner slide and a dwell is achieved by a linkage having small amplitude of motion during the part of the cycle in which the blank holder is to dwell, the blank holder and the inner slide being properly phased for the operation of the press.

One object of my invention is to provide a double action high speed press in which the number of strokes per unit of time performed by the press may be increased without exceeding the critical maximum drawing velocity of the metal being worked upon by the press.

A further object of my invention is to provide a double action press which may be operated at a greatly increased speed in order to produce a greater rate of work without exceeding the critical linear velocity of draw of the metal being worked upon.

Another object of my invention is to provide a double action press employing a common prime mover for the blank holder and the inner slide.

Other and further objects of my invention will appear from the following description.

In general, my invention contemplates the provision of a press frame on which an inner slide and blank holder are mounted. A common prime mover and operating gear train are mounted adjacent the bottom of the press which may be installed in a pit, or the like. The prime mover drives a crank carrying a link. To the other end of the link I pivot a high speed link, one end of which is carried by the frame. To the pin which is driven by the crank link and confined to a predetermined locus by the high speed link I attach a connecting rod for driving the inner slide. The construction is such that the inner slide will move downwardly through 225° of rotation of the driving crankpin and will move upwardly through 35° of the cycle of rotation of the driving crankpin, thus making for a slow downward movement of the inner slide and a rapid return movement of the slide. Another crankpin driven by the same prime mover reciprocates a head which is linked to one of two rocker shaft arms in order to oscillate the rocker

shaft. A crank arm carried by the rocker shaft is connected to the blank holder. The construction is such that the blank holder will move down and then dwell due to the linkages arriving at their small amplitude of motion positions at substantially the same time, dwelling while the inner slide does its work. After the work has been performed both the inner slide and the blank holder move to their top positions together.

In the accompanying drawings which form part of the instant specification and which are to be read in conjunction therewith and in which like reference numerals are used to indicate like parts in the various views:

Figure 1 is a sectional elevation showing a double action high speed press containing one embodiment of my invention.

Figure 2 is a sectional view taken along the line 2—2 of Figure 1.

Figure 3 is a sectional plan view taken along the line 3—3 of Figure 1.

Figure 4 is a motion diagram showing the motions of the inner slide and the blank holder of a conventional double action press.

Figure 5 is a motion diagram similar to that shown in Figure 4, showing the motions of the blank holder and the inner slide in a press according to the instant invention.

More particularly, referring now to the drawings, my press comprises a frame 10 of any suitable construction formed of welded steel plates having straight sides and secured by tie rods, or the like. Any suitable press frame may be employed. As can be seen by reference to Figure 2, the frame is provided with footings 12 adapted to support the press above a pit in which the driving train of the press is located. A prime mover, such as an electric motor 14, drives a flywheel 16 through V-belts 18. The flywheel is adapted to be clutched to a shaft 20 which carries a pinion 22 for rotation therewith. The pinion drives a gear 24 carried by and secured to a shaft 26. Secured to the shaft 26 for rotation therewith are a pair of pinions 28 which mesh with a pair of gears 30. As can be seen by reference to Figure 1, there are a pair of gears 30, one disposed on each side of the center line of the press. For purposes of convenience, the drives will be described with respect to one side only since the construction is symmetrical and in all respects the same on both sides of the press and like reference numerals will be used for the corresponding parts on opposite sides of the press. The gear 30 is secured to a shaft 32 which is formed with a pair of bearing disks 34 mounted in suitable bearings in the press frame. The center of the bearing disk 34 is coaxial with the center line of the shaft 32. Extending between the bearing disks eccentric of their axes of rotation I provide a crankpin 36 around which is positioned one end of a link 38. The other end of link 38 carries a pivot pin 40 around which I pivot one end of the high speed link 42, the other end of which is pivotally positioned to the frame by means of pin 44 carried by the frame. Around the pin 40 is also positioned the lower end of a connecting rod 46, the other end of which is connected to a reciprocating head 48 by means of pin 50. A plurality of rods 52 secure the inner slide 54 to the reciprocating head 48 for movement therewith. The upper ends of rods 52 are provided with threads 56 adapted to engage the nuts positioned within housings 60. The arrangement is such that the position of the slide 54 can be adjusted with respect to

the frame by the rotation of the nuts coaxing with the threaded portions 56 of the rods 52.

The outboard disk 34 is formed with a crankpin 62 carrying the lower end of a connecting rod 64. The upper end of the connecting rod 64 is connected to a pin 66 carried by a reciprocating head 68. A pair of rocker shafts 70 are carried by the frame. Secured to each rocker shaft for rotation therewith I provide a rocker crank 72 and a rocker arm 74. Each rocker crank 72 is connected to the reciprocating head 68 by a link 76 which extends between a pin 78 carried by the head 68 and a pin 80 carried at the end of rocker crank 72. As the reciprocating head 15 reciprocates the rocker shaft 70 will rock, moving the ends of rocker cranks 72 downwardly. As the head 68 continues to move downwardly the link 76 will be substantially horizontal and the rocker crank 72 will be substantially vertical. 20 In this position movement of the head 68 will produce negligible oscillation of the rocker shaft due to the fact that in the vicinity of zero degrees a variation of the angle will produce substantially no change in the length of the cosine. The 25 rotation of the rocker crank 72 will produce a corresponding rotation of the rocker arm 74. The end of the rocker arm 74 carries a pin 82 around which the lower end of connecting link 84 is pivoted. The other end of connecting link 30 84 is secured by pivot pin 86 to a reciprocating head 88. Rods 90 secure the head 88 to the blank holder 92 by means of adjustable connections 94. As the ends of rocker arms 74 move downwardly the blank holder 92 will move downwardly. When 35 the arm 74 extends substantially vertically the links 84 will likewise be substantially vertical, making an angle of 360° with the rocker arms 74. In this position rotation of the rocker arm will produce substantially no movement of the blank holder. The phasing of the parts is such that when the crankpin 62 reaches bottom dead center all of the parts will be in the vicinity of their small amplitude of motion positions so that the blank holder will dwell. Actually the blank 40 holder will oscillate very slightly through an amplitude of approximately .003 inch a number of times as each of the linkages passes and repasses its dead center position. The amplitude of motion is well within the elongation of the metal of the linkages so that the blank holder will rest immovably while the inner slide does its work. 45 Referring now to Figure 2, it will be seen that the crankpin 36 is approaching the top of its stroke, the direction of rotation being in a clockwise direction as viewed in this figure. During 50 225° rotation from the top dead center the inner slide will move downwardly at a comparatively slow speed. The curve of motion can be seen by reference to Figure 5. Bottom dead center is reached at approximately 225° of the press cycle. During the remainder of 135° of the press cycle, the inner slide will move upwardly starting slowly and then moving extremely rapidly to top dead center. The phasing of the high speed link 55 42 and the connecting link 38 is such that this result is accomplished. The time gained in the rapid return of the inner slide is used to reduce the velocity of the inner slide during its down-stroke. In this manner I am enabled to increase the speed of rotation of the press without exceeding the critical drawing speed. The results of my invention can best be seen by comparing the inner slide curve shown in Figure 4 of the 60 conventional press which moves with simple 65 70 75

harmonic motion with the curve of motion of my press shown in Figure 5.

The blank holder moves rapidly downwardly until the linkages approach their small amplitude of motion positions and then dwells during the period in which the inner slide does its work. After bottom dead center is reached both the blank holder and the inner slide move upwardly rapidly.

It will be seen, further, that I use advantageously a common prime mover and phase the motion of parts so that they are always correct for the operation of the press. A conventional double action press having an inner slide capacity of 700 tons, a blank holder capacity of 500 tons, an inner slide stroke of 28 inches and a blank holder stroke of approximately 18 inches was designed to run at seven strokes per minute to draw a particular metal. A high speed double action press of my design having precisely the same capacity was able to run at fourteen strokes per minute, doubling the output of the press without exceeding the critical drawing velocity for the particular metal.

It will be seen that I have accomplished the objects of my invention. I have provided a double action high speed press in which the number of strokes per unit of time performed by the press may be substantially doubled without exceeding the maximum drawing velocity of the metal being worked upon by the press. I have provided a double action press in which the draw starts comparatively slowly, thus minimizing the tendency of the metal to tear. I have provided a double action press capable of increased output employing a common prime mover for the blank holder and the inner slide.

It will be understood that certain features and subcombinations are of utility and may be employed without reference to other features and subcombinations. This is contemplated by and is within the scope of my claims. It is further obvious that various changes may be made in details within the scope of my claims without departing from the spirit of my invention. It is therefore to be understood that my invention is not to be limited to the specific details shown and described.

Having thus described my invention, what I claim is:

1. A high speed double action power press including in combination a frame, a slide mounted for reciprocation on the frame, a blank holder mounted for reciprocation on the frame, a prime mover, a crankshaft formed with a pair of crankpins, means for driving the crankshaft from the prime mover, a link having one end thereof pivotally carried by one of the crankpins, a second link having one end thereof pivotally secured to the press frame, a pin pivotally interconnecting the other ends of the first and second links, a connecting rod extending between the last named pin and the slide, a reciprocating head, a connecting rod extending between the second crankpin and the reciprocating head, a rocker shaft,

a pair of crank arms carried by the rocker shaft for rotation therewith, a link extending between the reciprocating head and one of the crank arms and forming a first toggle linkage therewith, means carried by the blank holder for movement therewith and a connecting link extending between said last named means and the other of the crank arms forming a second toggle linkage therewith, said toggle linkages being constructed and arranged to arrive at their small amplitude of motion positions at substantially the same time as said second crankpin approaches its bottom dead center whereby to cause the blank holder to dwell while the slide is performing its work.

2. A high speed double action power press including in combination a frame, a slide mounted on the frame for reciprocation with respect thereto, a blank holder mounted on the frame for reciprocation with respect thereto, a crankshaft formed with a pair of cranks, means for rotating the crankshaft, a pair of links and a connecting rod having one of respective ends pivotally connected at a common center, means for pivotally connecting the other end of one of the links to the press frame, means for connecting the other end of the other of the links to the first of said cranks, means for connecting the other end of the connecting rod to the press slide, a reciprocating head, a connecting rod between the other of said cranks and the head, a rocker shaft carried by the frame formed with a pair of crank arms, a link connecting the reciprocating head with one of the crank arms, means carried by the blank holder for movement therewith, and a link connecting said last named means with the other of the crank arms, the first of said last named links and the first of the said crank arms forming a toggle linkage, the second of said last named links and the second of the crank arms forming a second toggle linkage, the positioning of the first named links being such that the slide will move downwardly at a rate of speed less than that at which it moves upwardly with a uniform rotation of the crank, the positioning of the last named linkages being such that they will arrive at their small amplitude of motion positions at substantially the time the second of the cranks arrives at bottom dead center whereby the blank holder will dwell.

VASIL GEORGEFF.
